METHOD AND MEANS FOR REDUCING OR ELIMINATING LEVEL VARIATIONS OF MOLTEN METAL IN HIGH AMPERAGE ELECTROLYSIS CELLS

Jacques Bocquentin, Saint-Cloud, and Jean Givry, Saint-Jean-de-Maurienne, France, assignors to Pechiney, Compagnie de Produits Chimiques et Electrometallurgiques, Paris, France, a corporation of France

Filed July 5, 1961, Ser. No. 122,002

Claims priority, application France, Feb. 28, 1956,
709,429, Patent 1,143,879
2 Claims. (Cl. 204—243)

The present application is a continuation-in-part of our application Serial No. 641,530, filed February 21, 1957, now abandoned.

In the manufacture of aluminum, there are used more and more frequently electrolysis cells operating with 100,000 amperes and higher, in which the effect of the magnetic fields produce level variations of the upper surface of the liquid metal which lies on the bottom of the crucibles of these cells.

These level variations may be static, the upper surface of the metal remaining motionless. They may also result from the more or less rapid movements of the metal, which lowers appreciably the efficiency of the electrolysis.

Accordingly, it is an important object of the present invention to provide a method and means for reducing as far as possible these variations in the level of the liquid metal, or even to suppress them altogether.

High amperage electrolysis cells generally have a rectangular elongated shape, one of the sides of the rectangle being appreciably longer than the other. In the following description, the magnetic field and the current density at any point of the liquid metal will be defined by their projections on three coordinate axes starting from the same origin O, the central point of the bottom of the crucible of the electrolysis cell. The Ox axis is parallel to the longer side of the electrolysis cell; the Oy axis lies in the same horizontal plane as the Ox axis and is perpendicular to the latter (hence, parallel to the smaller side of the rectangle). The Oz axis is vertical and, hence, perpendicular to the xOy plane.

Let B denote the value of the magnetic field at a given point, and Bx, By, Bz the projections of B on the Ox, Oy and Oz axes respectively;

Let J denote the value of the current density, and Jx, Jy, Jz, the projections of J on the Ox, Oy and Oz axes respectively.

The static level variations of the upper surface of the liquid metal are proportional to the products of the vertical component of the field by the horizontal components of the current density, i.e.

BzJx and BzJy

It has been proposed to suppress the horizontal longitudinal currents Jx by judiciously dimensioning (calculating) the conductors which connect one cell to the succeeding cell so as to distribute the current properly in the bottom of the crucible. This arrangement—which has been proposed by others and is not claimed here—is effective.

It has likewise been suggested by others and, hence, is not the subject of claims herein, to reduce or suppress the transverse currents Jy by maintaining over the entire periphery of the liquid metal sloping masses of solidified fluorides so as to obtain a cathodic surface substantially equal to the anodic surface. Good electrolysis efficiencies are obtained in this manner, even though magnetic fields still exist. However, the more the magnetic fields are reduced, the better and the more stable is the operation of

2

the electrolysis cell, should the current happen to spread out accidentally, that is to say when the Jy component is not zero.

It is heretofore been proposed by others—and is not the subject of claims herein—to reduce the magnitude of the magnetic field B by dividing the conductors outside the cell into as large a number as possible of smaller conductors, arranged with their upper ends simulating sheets and spaced from the metal. A marked improvement is achieved in this manner, but these arrangements interfere sometimes with the work of the operators.

Finally, it has been proposed to suppress the magnetic fields by placing the conductors far away from the liquid metal and by placing, side by side, conductors through which flow currents in opposite directions. Unfortunately, this suggestion—made by others and not claimed herein—requires a large investment in conductors and leads to excessive power losses.

The present invention, which is based upon applicants' researches, makes it possible to avoid the above disadvantages while attaining a satisfactory stable operation of high amperage electrolysis cells even when they are arranged lengthwise, that is to say, when the long sides of the rectangle of one cell are placed in the prolongation of the long sides of the rectangle of the preceding and of the succeeding cells in the direction of the current flow.

The invention, its advantages and the manner of its application, will be described with reference to the annexed schematic drawings which relate to an improved system for the igneous electrolysis of a molten bath of metallic compounds to produce molten metal in a cell comprising a crucible for containing the molten metal, an anode vertically supported above said crucible, a cathode, a feeder system for supplying current to the anode, current outlet means associated with said cathode, and conductor means connecting the current outlet means of the cell to the feeder system of a succeeding adjacent cell.

In the drawings:

FIGURE 1 is a perspective diagrammatic view showing the volume of liquid metal lying in the bottom of the crucible of the electrolysis cell;

FIGURE 2 shows the "lengthwise" arrangement of a line of cells successively traversed by a current of the same intensity, the direction of the current being indicated by an arrow;

FIGURE 3 is a view in vertical section and perpendicular to its greatest length of the cell crucible;

FIGURE 4 is a plan view of the cell of FIGURE 3;

FIGURE 5 is a view in elevation of two successive cells, in the direction of their greatest length, the current being supplied to the cells at one end only;

FIGURE 6 is a view similar to that of FIGURE 5, but with a modified current supply, and

FIGURE 7 shows a sectional view of the electrolysis cell as in FIGURE 3, together with curves, the intersection of which enables determination of the optimum position of the conductors according to the present invention, as will be described below.

FIGURE 8 is also a view in vertical section and perpendicular to its greatest length of a cell in a "lengthwise" arrangement of a line of cells (as illustrated in FIGURE 2) wherein the conductors are shown disposed as they were according to an actual example of the prior art practice, while

FIGURE 9 is a similar view of the same cell, but with the conductors disposed in accordance with the teachings of the present invention.

In the various figures, the same or equivalent parts are designated by the same reference numerals. In the figures, 1 is the crucible; 2, 2 represent the feeder system ("monture") which receives the current leaving the preceding cell and distributes it to the anode system of the

cell. 3, 3 represent the conductors in their means position disposed parallel to the greatest length of the cell. 3', 3' (FIG. 4) represent the ends of the conductor which collect the current leaving the preceding cell; they are electrically connected to the feeder system 2, 2 which, in the case of FIG. 4, is supplied with current at one end only. This is also true in the case of the two successive cells shown in FIGURE 5, where the feeder 2 is supplied at one end only.

In contrast, FIGURE 6 shows an arrangement of two cells similar to those of FIGURE 5, but wherein the feeder system 2 is supplied with current at its both ends. The current leaving the preceding cell and brought by conductor 3' is divided in this case into two currents, and a conductor 4—parallel to 3—connects with the other end of feeder system 2. With such an arrangement, the conductors 3 in FIGURES 3 and 4 would represent the mean position of the system of conductors 3 and 4 of FIGURE 6. These conductors 3 and 4 can be arranged as a plurality of conductors of smaller size disposed to simulate sheets, as previously proposed.

The lengthwise arrangement of the electrolysis cells is adopted very often because it saves space and facilitates the operation; however, the magnetic effects may be particularly large.

The method which is the object of the present invention consists in nullifying the magnetic effects at the center O of the crucible of the electrolysis cell. While these effects will still exist on the rest of the cell surface, they will be very weak in the neighborhood of the center O and, in practice, their magnitude shows a certain symmetry with reference to that point, which insures sufficient stability in the operation of the electrolysis cell.

The vertical component B_z of the field produced by the horizontal conductors situated near the cell is reduced to zero by reason of symmetry.

The transverse component J_y of the current density is likewise reduced to zero at the center of the cell for reasons of symmetry, and so is J_x ; hence, at that point, there are no magnetic effects of static origin.

The effects of dynamic origin depend on the value of a rotational vector R which can be calculated by means of the values of the components B_x , B_y , B_z and of the current densities J_x , J_y , J_z and their partial derivatives.

The mathematical expressions for the projections of the vector R on the Ox , Oy and Oz axes are as follows:

$$R_x = B_x \frac{dJ_x}{dx} + B_y \frac{dJ_x}{dy} + B_z \frac{dJ_x}{dz} - J_x \frac{dB_x}{dx} - J_y \frac{dB_x}{dy} - J_z \frac{dB_x}{dz}$$

$$R_y = B_x \frac{dJ_y}{dx} + B_y \frac{dJ_y}{dy} + B_z \frac{dJ_y}{dz} - J_x \frac{dB_y}{dx} - J_y \frac{dB_y}{dy} - J_z \frac{dB_y}{dz}$$

$$R_z = B_x \frac{dJ_z}{dx} + B_y \frac{dJ_z}{dy} + B_z \frac{dJ_z}{dz} - J_x \frac{dB_z}{dx} - J_y \frac{dB_z}{dy} - J_z \frac{dB_z}{dz}$$

At the center O of the cell, B_x is zero and so are its partial derivatives; also,

$$\frac{dJ_x}{dz}$$

is zero and so are

$$\frac{dJ_x}{dy}$$

and

$$\frac{dJ_y}{dz}$$

if the precautions, mentioned above for insuring the distribution of the current in the bottom of the cell, have been taken.

Only the vertical component J_z of the current remains as $J_x = J_y = 0$. The derivative

$$\frac{dB_z}{dz}$$

variation of the vertical component of the field along the

height of the liquid metal, is also zero. The derivative

$$\frac{dJ_z}{dy}$$

variation of the vertical component of the current density along the transverse direction, is zero, J_z being practically constant over a very wide zone about the center O.

Hence, at the center O of the cell, the components R_x and R_z of the rotational vector are zero and there remains:

$$R_y = B_y \frac{dJ_y}{dy} - J_z \frac{dB_y}{dz}$$

Therefore, rotational movement of the metal about an axis parallel to Oy may occur at the center of the cell. To prevent this, R_y must be reduced to zero. However, J_z , the vertical component of the current density, cannot be reduced to zero, neither can

$$\frac{dJ_y}{dy}$$

which expresses the variation of the transverse horizontal component of the current density in the transverse direction.

Hence, it will only be possible to obtain the elimination of the magnetic effects at the center of the cell—which is the object of the present invention—by nullifying B_y , the transverse component of the magnetic field, and

$$\frac{dB_y}{dz}$$

which expresses the variation of this transverse component of the field along the vertical.

In order to compute the component B_y , in FIGURE 3 let

“ a ” be the distance between the feeder 2 and the Oz axis;

“ b ” the vertical distance of the line passing through the middle (mean) points of conductors 2 to the center of the cell;

“ c ” the distance between conductor 3 and the Oz axis; and

“ d ” the vertical distance between O and a line passing through the middle (mean) points of conductors 3.

“ αI ” will designate the intensity of the current supplied to feeder 2 at the side of the preceding cell (FIG. 4), and “ $(1-\alpha)I$ ” the intensity of the current supplied to feeder 2 from the opposite side (FIG. 6). In the case of FIGURE 5, $\alpha=1$.

The field produced at O by the current flowing through conductors 2 and 3 is calculated in the same way as if it were the case of conductors of unlimited (indefinite) length carrying the currents which actually flow through the conductors in the Yoz plane. Experience proves that there is obtained an approximation which is sufficient for practical purposes.

The following results are obtained:

	Conductors 2,2	Conductors 3,3
B_y	$2I(\alpha-\frac{1}{2}) \frac{b}{a^2+b^2}$	$2I(\alpha-\frac{3}{2}) \frac{d}{c^2+d^2}$
$\frac{dB_y}{dz}$	$2I(\alpha-\frac{1}{2}) \frac{(b^2-a^2)}{(a^2+b^2)^2}$	$2I(\alpha-\frac{3}{2}) \frac{(c^2-d^2)}{(d^2+c^2)^2}$

To reduce simultaneously to zero B_y and

$$\frac{dB_y}{dz}$$

it is necessary to have the following two conditions:

Equation 1

$$(\alpha - \frac{1}{2})b(c^2 + d^2) + (\alpha - \frac{3}{2})d(a^2 + b^2) = 0$$

and

Equation 2

$$(\alpha - \frac{1}{2})(b^2 - a^2)(d^2 + c^2)^2 + (\alpha - \frac{3}{2})(c^2 - d^2)(a^2 + b^2)^2 = 0$$

The term α can be eliminated from the two equations. We then have

EQUATION 3

10

$$d(b^2 - a^2)(d^2 + c^2) + b(d^2 - c^2)(a^2 + b^2) = 0$$

which can replace the second of the above equations.

Given a and b , i.e. the position of the feeders 2—2 which is generally determined by the requirements of construction and operation of the cell, it will be seen that the third equation represents a cubic curve independent of the current distribution α in the feeders.

The first equation represents a circle the radius of which varies with α . The distance a is generally small; if we assume that it is zero, then, we obtain conditions as illustrated in FIGURE 7. Here, 5 is the cubic curve on which the conductors 3, 3 must always be placed; 6 is the circle corresponding to $\alpha = 1$, i.e. the situation where current is supplied at one side only, with circle 6 having a radius of $b/2$; 7 is the circle corresponding to $\alpha = \frac{3}{2}$ and a radius of $5b/2$. The mean position of conductors 3 will then be at 8 in the case where the feeder system is supplied with current at one end only, and at 9 when the feeder system is supplied with current at both ends, with $\frac{3}{2}$ of the current entering at the end nearest the preceding cell, $\frac{1}{2}$ by the other end.

The position of the conductors is then determined by the following table:

	$\alpha = 1$	$\alpha = \frac{3}{2}$
c/b	0.5	1.7
d/b	0.35	0.7

It has been assumed that the height b of the feeder 2 above the bottom of the crucible is known. This is the case most often; on the other hand, it is possible to assume that one of the dimensions c or d is known and the above equations can then be solved without departing from the scope of the invention.

The above defined position for the side conductors represents the mean point of the conductors which can be divided into as large a number as possible of parallel conductors arranged in a manner simulating sheets about this mean point.

The examples given below, which are not given by way of limitation, will enable a better understanding of the advantages resulting from the application of the present invention.

Example 1

A 100,000 ampere electrolysis cell, arranged lengthwise and the feeder 2 of which was supplied with current at both ends (FIG. 6), presented a bad distribution of the magnetic fields, namely, a weak field at the side of the preceding cell, a strong field at the center and very strong field at the side of the succeeding cell. The liquid metal on the bottom of the cell's crucible was subjected to rotational movement and its upper surface presented irregular variations of level which attained a maximum of 5 centimeters.

The operation of the cell was very unstable; the bath froze against the walls of the crucible on the side where the field was weak, thereby reducing excessively the active zone and, by contrast, it was impossible to maintain the inclined mass (talus) of solidified fluorides on the opposite side (the side of the next cell).

By disposing the conductors 3, 3 according to the method of the present invention, the magnetic effects be-

come zero at the center O of the cell. They are substantially symmetrical with reference to the point O. The variations of level of the upper part of the liquid metal practically disappear and it is possible to maintain regular inclined masses of solidified fluorides over the entire periphery of the crucible. The operation of the cell is much more stable and there is obtained a reduction of the energy consumed amounting to 800 kwh. per ton aluminum.

Example 2

A 50,000 ampere electrolysis cell, equipped with pre-baked anodes, arranged lengthwise and having feeders 2, 2 supplied with current on one side only (FIG. 5), and with the conductors 3, 3 placed on a level with the bottom of the crucible ($d=0$), was subjected to magnetic fields having a very large horizontal component B_x at the side of the preceding cell, a component half this value in the vicinity of point O which is reduced to zero on the opposite side but having, in contrast, a large vertical component B_z .

The cell operated in a very unstable manner and all the phenomena described in Example 1 were observed. By changing the position of the conductors 3, 3 in accordance with this invention to point 8 on FIG. 7, an improvement similar to the one already described was obtained, together with a more stable operation. Moreover, the efficiency of the electrolysis was increased by more than 3%, changing from 84 to 87% of the theoretical efficiency.

It should be mentioned that in the practical design of a cell system, applicants generally first select convenient values of a and b and that is, the position of the feeders or bus-bars ("monture"), these values being governed by practical considerations, such as ready access, etc. The values of c and d are then calculated, i.e. determined for various values of α in accordance with the teachings of the present invention. The solution finally adopted is that which appears the most practical at the same time for α , c and d . The actual procedure in the determination of the most suitable values is set out in detail in the following example:

Example 3

The advantages of the present invention will be further apparent from a consideration of the following detailed example, taken in connection with FIGURES 8 and 9, which relate to a cell of an actual commercial plant for the production of aluminum.

FIGURE 8 illustrates the disposition of the conductors in one cell of a line of Soderberg cells arranged "lengthwise" which were in actual operation before the present invention. FIGURE 9 represents the same cell but with the conductors disposed in accordance with the teachings of the present invention. In both instances, the cell operated with a current of 90,000 amperes. The cell of FIGURE 8 had the following characteristics:

The feeder system ("monture") 2, 2 was supplied at one end only from the preceding cell, hence

$$\alpha = 1$$

60 "a" the mean distance between the feeder 2 and the Oz axis, was 0.50 m.;

"b," the vertical distance of the line passing through the middle (mean) points of conductors 2, 2, to the center of the cell, was 2.60 m.;

65 "c," the mean distance between the Oz axis and the conductor 3 collecting the current from the cathode was 2.90 m.;

70 "d," the vertical distance between the center of the cell and a line through the middle (mean) points of conductors 3, 3, was zero, that is to say, the conductor 3, 3 were positioned on the Oz axis.

The cells suffered from severe magnetic effects: There took place an "unlevelling," or level deformation, of the separating surface between the bath and the metal of the order of 10 cms., this surface rising in the direction of

the current flow in the cells, i.e. rising in the direction from A to B (cf. FIG. 2). Further, there were observed systematic temperature differences of the bath between the two ends of the cell, the zone where the level of the metal was highest being the coldest.

Additionally, the shape of the solidified lateral inclined mass ("talus") of fluorides of the bath was asymmetrical. It was quite pronounced in the zone (region) B (FIG. 2) where the height of the metal was a maximum and where, also, several centimeters of mud appeared on the bottom of the crucible. An inclined frozen mass ("talus") was practically non-existent on the opposite side A where the bath and the metal appeared to be in continuous agitation. At the same time, the operation of these cells were unstable and inefficient; the operating results were inferior to those of smaller cells; the average voltage was higher (by about 0.15 volt) and the yield of the current smaller (by about 5%). Actually, the yield of the current (Faraday yield) was 82% in lieu of 87%.

The cell of FIGURE 8 was subsequently modified in accordance with the teachings of the present invention in the manner illustrated in FIGURE 9. That is, the feeders 2, 2 were left in the same position but were supplied with current at both ends. FIGURE 9 shows the cubic curve 5 satisfying the equation given earlier in the specification, and further shows the various circles corresponding respectively to the value of

$$\begin{aligned}\alpha &= 1 (100-0) \\ \alpha &= 0.9 (90-10) \\ \alpha &= 0.8 (80-20) \\ \alpha &= 0.7 (70-30), \text{ and} \\ \alpha &= 0.6 (60-40)\end{aligned}$$

As will be seen from FIGURE 9, the most advantageous position of the conductors 3, 3 is that corresponding to $\alpha=0.8$ (80-20), because the conductors are not under the sub-structures of the cell and, yet, are not too far away therefrom. The conductors 3, 3 are those which collect the current leaving the cathode, and 4 is the conductor which supplies the 20% of the amperes to the end B of the feeder system 2, 2.

As shown on FIGURE 9, the point of intersection of the circle 80-20 with the cubic 5 is the mean point of the conductor assembly 3, 3 and 4. The coordinates of the conductors are

$$\alpha=0.50 \text{ m. } b=2.60 \text{ m. } c=2.80 \text{ m. } d=1.56 \text{ m.}$$

When the cell was modified in the manner just described, the detrimental effects of magnetic origin disappeared in the cell: the upper surface of the liquid metal became substantially horizontal, the solidified inclined masses ("talus") of the bath were uniformly shaped and

easy to maintain. Moreover, the energy consumption (kw./hour) per ton of aluminum was reduced from 16,750 kw./h. to 15,250 kw./h. per ton, that is to say, a gain of 1500 kw. per hour or 9%.

In the appended claims, the several symbols have the meaning given to them in the present specification.

We claim:

1. An improved system for the igneous electrolysis of a molten bath of metallic compounds to produce molten metal, and wherein detrimental deformation of the level of the molten metal is substantially inhibited, comprising in combination: a plurality of successively lengthwise disposed cells each including a crucible for containing the molten metal, an anode vertically supported above said crucible, a cathode; a system of feeders for supplying current to each said anode, said feeders being spaced laterally from the center of the crucible by a distance a and vertically above said crucible by a distance b , the distance a always being smaller than b , said distances a and b being determined arbitrarily; current outlet means associated with each said cathode; conductor means connecting the current outlet means of each cell to the feeders of the succeeding adjacent cell; said conductor means being spaced laterally from the center of the crucible by the distance c and vertically below and relative to the center of the crucible by the distance d , said conductor means being located at the point of intersection of a cubic curve passing through the center of the crucible and satisfying the equation

$$d(b^2-a^2)(d^2+c^2)+b(d^2-c^2)(a^2+b^2)=0$$

and a circle, likewise passing through said center and satisfying the equation

$$(\alpha-\frac{1}{2})b(c^2+d^2)+(\alpha-\frac{3}{2})d(a^2+b^2)=0$$

in which α designates the proportion of the intensity of the current supplied to the feeders at the end nearest the preceding cell, α being 1 when all of the current is supplied to the end of the cell nearest the preceding cell.

2. A system according to claim 1, wherein the conductor means comprises a number of parallel conductors, and the lateral distance c equals the mean position of the parallel conductors from the center.
